Joseph A. Winger, Greenwich, Conn., assignor to Texaco
Inc., New York, N.Y., a corporation of Delaware

Filed May 22, 1962, Ser. No. 70,235

Term of patent 14 years

(Cl. D52—2)

T1-1.

FIGURE 1 is a front perspective view of a compressed air supply cart, showing my new design; FIGURE 2 is a side elevational view thereof; and FIGURE 3 is a rear elevational view thereof.

The undisclosed side of the compressed air supply cart is substantially the same in appearance as the side shown in FIG. 2.

I claim:

The ornamental design for a compressed air supply cart or similar article, as shown and described.
